UNITED STATES PATENT OFFICE.

JOHN CHARLES REGINALD McCRUDDEN, OF HURSTVILLE, NEAR SYDNEY, NEW SOUTH WALES, AUSTRALIA.

FIRING AND SAFETY MECHANISM FOR FIREARMS.

Application filed March 26, 1926, Serial No. 97,556, and in Great Britain September 22, 1924.

This invention relates to trigger-controlled firing-mechanism for firearms of the kind wherein a sear, normally engaging the firing-bent or notch of a bolt, cocking-piece, tumbler or equivalent coacting element of the firing-mechanism, is prevented from accidental disengagement therefrom by a locking-member which is carried by and movable as one with the trigger and is normally 5 presented in position to prevent movement of the sear, the pulling of the trigger having for effect to withdraw the locking-member from engagement with the sear immediately before the latter is itself withdrawn, as a 10 result of continued actuation of the trigger, from engagement with said firing-bent or notch. The primary object of the present invention is to provide an improved construction, applicable in cases wherein the 15 trigger and the sear are each constituted by a pivoted lever, with a view more effectually to obviate risk of accidental discharge of the firearm as a result of the sear being "jarred off" by the shock due to a fall, or to a sudden 20 blow, when the weapon is cocked; a further object being to ensure that, in an automatic quick-firing weapon, release of the finger-pressure upon the trigger (as when the operator is put out of action) will result 25 in the sear becoming automatically relocked, so that the firing of the weapon will cease.

According to the present invention the trigger-axis and sear-axis are so placed relatively to one another and to the point of mutual engagement between the locking-member and the sear that lines joining said point with the respective axes are substantially at right angles to one another whilst the sear-nose, which engages in the firing-bent or 30 notch of the bolt or other coacting element of the firing-mechanism, is situated approximately in a prolongation of the line joining the trigger-axis with said point of mutual engagement and out of the line joining the 35 sear-axis with the same point.

The locking-member may be constituted by an upwardly-extending arm of the trigger-lever whilst the sear may have a rearwardly-extending arm adapted, so long as 40 the trigger remains in normal position, to rest upon said trigger-arm and thus retain the sear-nose (constituted by the rear extremity of said sear-arm) in engagement 45 with the firing-bent or notch; the mutual engagement of the sear-arm and trigger-arm

being such as to permit of the trigger-arm being moved from beneath the sear-arm before the trigger comes into action to withdraw the sear-nose from engagement with said firing-bent or notch. For the purpose 50 of actuating the sear, the upwardly-extending trigger-arm may have a forward projection adapted, when the trigger has been pulled so far as to unlock the sear, to engage a downwardly-projecting arm on the sear so 55 as to withdraw the sear from engagement with said firing-bent or notch. The sear may also be provided with a forwardly-extending arm having freedom for limited downward movement, this arm resting upon a cushion- 60 spring adapted to reinforce the action of the sear-spring and deaden or partially absorb any jar or shock tending to displace the sear from engagement with said firing-bent or 65 notch.

Further, the trigger may be provided with a safety-lever whereby to prevent its accidental actuation, this safety-lever being itself moved to and held locked in the operative or safety position and in the inoperative 70 position alternatively by means of a cam-lever mounted, in the pistol hand-grip or equivalent part of the stock, in such position as to be readily felt, more especially when in the safety position, by the trigger-hand 75 when the latter is applied to the weapon, even in the dark.

One form of the invention is illustrated in the accompanying drawing, which shows, in partly sectional side elevation, only such 80 parts of the firing mechanism as are required for the purpose of explanation.

The trigger 11, pivoted at 12, and presenting the curved finger-piece 13 behind the trigger-guard 14, tends under stress of the 85 trigger-spring 15 to occupy the normal or resting position (shown in full outline) determined by the arm 16 contacting with the stop 17. The sear 18, pivoted at 19 about an axis situated above and forward of the 90 trigger-axis 12, has a rearwardly and upwardly extending arm 20 the rear extremity or nose 20^a of which, normally held raised by the sear-spring 21 as indicated, is adapted 95 then to engage in the firing-bent or notch of the bolt, cocking-piece, tumbler, or equivalent coacting element (not shown) of the firing-mechanism, so as to prevent the discharge of the weapon. The sear 18 has also 100 a forwardly and downwardly extending arm 110

22 which rests upon a coiled cushion-spring 23 held in a socket 24, the upwardly-presented lip of which serves as a stop adapted to oppose a positive limit to the movement 5 of the sear under the stress of its spring 21; the end of the sear normally resting just clear of this stop, so that combined action of the cushion-spring 23 and sear-spring 21 will deaden or partially absorb any jar or 10 shock upon the sear-nose 20^a, such as is liable to arise from the reaction of a powerful recuperator-spring (not shown) in automatic or semi-automatic small-arms and like 15 weapons.

15 The rearwardly and upwardly extending arm 20 of the sear 78 has on its lower side a notch 25 in which engages an upwardly extending arm 26 of the trigger 11; both the rearward portion of the sear-notch 25 20 and also the upper extremity of the trigger-arm 26 being preferably stepped as indicated at 27, and the sear normally resting upon the arm 26 with a downward pressure towards the trigger-axis 12, so that the parts 25 when at rest tend to remain in the position shown. The plane at which the arms 20 and 26 thus contact with one another extends in the direction, approximately, of the sear-axis 19, and the notch 25 is made long 30 enough, towards the sear-axis 19, to allow of the extremity of the trigger-arm 26, when the trigger is pulled, passing clear of its engagement with the step 27 on the sear; the notch 25 being also made deep enough, 35 when the trigger-arm 26 has been thus moved clear of the sear-step at 27, to allow such depression of the sear-arm 20 as is necessary to release the sear-nose 20^a from the firing-bent or notch of the bolt or equivalent element of the firing-mechanism. The trigger-arm 26 has formed upon it a forward projection 28 adapted, as soon as the arm 26 has been moved clear of the sear-step at 27, to encounter and move forwards 40 (as indicated by the dotted outline) a downwardly-extending arm 29 on the sear 18, whereby, on the trigger being pulled to its full extent, the sear-arm 20 is depressed against the stress of the sear-spring 21 so 45 as to release the sear-nose 20^a from the firing-bent or notch of the bolt (or equivalent element) and thus bring about the discharge of the weapon.

50 The substantially vertical rear surface of the sear-nose 20^a, where the latter normally engages in the firing-bent or notch just referred to, is situated above the level of the sear-axis 19 and out of the direct line of the thrust, towards said axis, exerted by 55 the bolt or equivalent element when the weapon is cocked, so that the sear 18 then has freedom for a slight rocking movement, about its axis 19, permitted by the cushion-spring 23; such movement, whilst sufficient 60 to absorb the effect of jarring or sudden

shock, being nevertheless insufficient to release the sear-nose 20^a from the firing-bent or notch of the bolt or equivalent element, so that danger of accidental discharge of the weapon due to such cause is eliminated. 70

It will be observed that if, after a discharge, or during a series of discharges in the case of an automatic or semi-automatic small-arm, the pressure on the finger-piece be released, the trigger and sear will at once 75 return to their normal position, so that the firing of the weapon will automatically cease.

In conjunction with the above, the trigger 11 may be provided (as in frequent practice) with a safety-device for enabling it to be positively locked against actuation until the weapon is to be actually discharged. In the example illustrated, the locking is effected by the substantially horizontal arm 80 30 of a bell-crank lever pivoted at 31 about a transverse axis within the upper part of the hollow pistol-grip 32 of the fire-arm, the arm 30 extending forwards through an opening 33 in the front wall of the grip 32 so as, 85 by bearing against a projection 34 on the rear side of the finger-piece 13 of the trigger, to prevent the latter from being pulled. From the pivot 31, a second arm 35 of this bell-crank lever extends downwards within 90 the hollow pistol-grip 32, the lower end of this arm 35 being rearwardly directed and forked as at 36 to carry a transverse pin 37 which engages a cam-slot 38 in a small cam-lever 39 pivoted at 40 to swing in or parallel to the plane of movement of the arm 35. The arm 35 is inaccessible, but can at will be moved by means of the cam-lever 39 so as, 95 by shifting the bell-crank lever from the full-line to the dotted-line position, to withdraw the arm 30 from the position wherein it prevents the pulling of the trigger. For this purpose the end of the cam-lever 39 projects outside the pistol-grip 32 through a slot 41 provided therein, the end of the cam-lever 100 being furnished with a knob 42 which, when the arm 30 is in the operative position shown in full outline, is presented towards the rear of the pistol-grip so as to be readily felt by the trigger-hand of the operator, even in the dark. The cam-lever slot 38 is 105 of such form, and so placed relatively to the pin 37 and axis 31, as to necessitate the exertion of a slight effort to move the safety-lever 30, 35 from the operative to the inoperative position, the cam-lever 39 itself being made preferably from springy sheet-metal so as, whilst adapted so to hold the pin 37 as to resist any tendency of the safety-lever 30, 35 to become shaken or jarred out 110 of operative position, to be capable of yielding when the knob 42 is forced by the hand of the operator from the full-line to the dotted-line position and vice versa. When the safety-lever 30, 35 is in the inoperative po- 115

sition, the knob 42 of the cam-lever 39 lies snugly against the forward end of the slot 41 in the bottom of the pistol-grip 32, so as to be out of the way and protected from involuntary actuation, but can readily be returned to the operative or safety position by inserting a finger into a recess or groove (not shown) provided for the purpose and forming a widened mouth for the slot 41.

10 It will be obvious that, instead of an arm such as 26 on the trigger entering a notch such as 25 in the sear, the sear 18 might have a depending arm entering a notch in the upper end of the trigger-arm 26, provided always that the mutual engagement of the trigger and sear is such that, so long as the trigger occupies its normal or resting position, the sear is prevented from becoming disengaged from the firing-bent or notch of 20 the coacting element of the firing-mechanism, but is freed when the trigger is pulled so as to depress the sear-nose 20^a.

I claim:—

1. Trigger-controlled firing-mechanism for fire-arms of the kind referred to, comprising a trigger, a sear, mutually engaging members on the trigger and sear respectively whereby the trigger is adapted to prevent movement of the sear out of engaging position with the bent or notch until the trigger is pulled, said trigger and sear being pivotally mounted on axes so placed relative to one another and to the point of mutual engagement between the sear and the trigger that lines joining said point with the respective axes are substantially at right angles to one another, a nose on said sear for engaging the firing bent or notch, said nose being situated approximately in a prolongation of the line joining the trigger axis with said point of mutual engagement but out of line joining the sear axis with said point, resilient means holding the nose of said sear

in position for cooperation with the bent or notch, and coacting members on the trigger and sear respectively for moving said nose out of the bent or notch by a continuing pull on the trigger, the initial movement of which disengages said mutually engaging members, substantially as set forth. 45 50

2. Trigger-controlled firing-mechanism as claimed in claim 1, wherein said trigger is provided with an upwardly extending locking arm, and said sear is provided with a rearwardly extending arm, carrying said nose, adapted, when the trigger is in normal position, to rest upon said upwardly extending arm to thereby retain the nose of the sear in position to engage the firing bent or notch, the mutual engagement between said 60 sear and trigger being such as to permit the trigger arm to be moved to release said sear arm before the trigger comes into action to withdraw the nose of the sear from its position of engagement with the firing bent or 65 notch of the co-acting element of the firing mechanism, substantially as set forth.

3. The trigger-controlled firing-mechanism as claimed in claim 1, in which said sear is provided with a forwardly extending arm 70 cooperating with a stop member for limiting rebound movement of said sear when the trigger is released after firing and a cushion spring engaging said forwardly extending arm, for absorbing rebound shock of said 75 sear, substantially as and for the purpose set forth.

4. In trigger-controlled firing mechanism as claimed in claim 1, the combination therewith of a safety lever, adapted to be moved 80 into position to cooperate with the trigger to prevent the latter from being pulled and a cam lever for moving and controlling the position of said lever, substantially as and for the purpose set forth.

JOHN CHARLES REGINALD McCRUDDEN.
